TABLE

William Joseph Carr, Gardner, Mass., assignor to Heywood-Wakefield Company, Gardner, Mass.,
a corporation of Massachusetts

Application July 23, 1948, Serial No. 147,734

Term of patent 7 years

(Cl. D23—14)

To all whom it may concern:

Be it known that I, William Joseph Carr, a citizen of the United States, residing at Gardner, in the county of Worcester and Commonwealth of Massachusetts, have invented a new, original, and ornamental Design for a Table, of which the following is a specification, reference being had to the accompanying drawing, forming part thereof, in which:

Fig. 1 is a view in perspective of a table showing my new design.

Fig. 2 is a view in side elevation of the table shown in Fig. 1.

Fig. 3 is a view in end elevation of the table shown in Fig. 1.

Fig. 4 is a top plan view of the table shown in Fig. 1.

I claim:

The ornamental design for a table, substantially as shown.

WILLIAM JOSEPH CARR.
